UNITED STATES PATENT OFFICE.

JOHN N. HELTZEL, OF WARREN, OHIO.

SIDEWALK AND ROAD FORM.

1,141,057.

Specification of Letters Patent. Patented May 25, 1915.

Application filed December 5, 1914. Serial No. 875,671.

To all whom it may concern:

Be it known that I, JOHN N. HELTZEL, a citizen of the United States, residing at Warren, in the county of Trumbull and

5 State of Ohio, have invented a new and useful Sidewalk and Road Form, of which the following is a specification.

The device constituting the subject matter of this application is a form adapted to 10 be employed in the making of curbs, and particularly in the making of curbs which are combined with a road bed.

One object of the present invention is to provide a means whereby the curb and the 15 road bed may be formed as a monolithic structure.

A further object of the invention is to provide novel means whereby the front plate is suspended from the back plate of the mold.

20 Another object of the invention is to provide novel means whereby the front plate and the back plate, or the back plate if the latter is used alone, may be adjusted vertically upon a supporting member or stake.

25 Another object of the invention is to provide means whereby the back plate and connected parts may be adjusted in a horizontal direction, to the end that the angle between the back plate and the vertical may be 30 changed.

It is within the scope of the present disclosure to improve generally and to enhance the utility of devices of that general type hereinafter described.

35 With the above and other objects in view which will appear as the description proceeds, the invention resides in the combination and arrangement of parts and in the details of construction hereinafter described 40 and claimed, it being understood that changes in the precise embodiment of the invention herein disclosed can be made within the scope of what is claimed without departing from the spirit of the invention.

45 In the accompanying drawing:—Figure 1 is a perspective view showing a curb form embodying the present invention; Fig. 2 is a transverse section of the curb form, a portion of the road bed and the curb appearing 50 in section; Fig. 3 is a perspective of one of the spacing plates; Fig. 4 is a perspective of the key which cooperates with the spacing plate shown in Fig. 3; Fig. 5 is a fragmental section view showing one application of the 55 mold under conditions in which certain ele-

ments of the mold as shown in Fig. 2 are omitted. Fig. 6 is a fragmental perspective showing the support and the bracket carried thereby.

In carrying out the present invention there 60 is provided a back plate 1 equipped with a top flange 2 having a depending lip 3. In the top flange 2, openings 20 are formed at intervals. The back plate 1 is provided with a bottom flange 4 having an upstanding 65 lip 5.

A plurality of supports preferably in the form of angle members 6 are provided, each support 6 embodying a flange 7 and a flange 8. In the flange 8 adjacent the top of the 70 support 6 a plurality of openings 9 are formed and in the flange 8 adjacent the bottom of the support openings 10 are formed.

The invention embodies a bracket preferably in the form of a plate 11, the same being applied to the flange 8 of the support 6. In its upper edge the bracket plate 11 is provided with a notch 12 receiving the top lip 3 of the back plate 1, the construction being 80 such that when the top lip 3 is lodged in the notch 12, the lip will be in engagement with the flange 7. The bracket plate 11 is provided with an upright slot 14, having horizontal branches 14^a. Securing elements 15 85 which may be bolt and nut structures lie in the slot 14 and may be engaged in any of the openings 9 in the flange 8 of the support 6. Owing to the foregoing details, the bracket 11 may be adjusted vertically or horizontally, 90 and with it the back plate 1.

Disposed transversely of the support 6 and in engagement with the flange 8 thereof is an abutment 16 which if desired may comprise a handle 17. The abutment 16 is supplied with a longitudinal slot 18. Engaged in the slot 18 and adapted to be engaged in any of the openings 10 of the flange 8 is a securing element such as a wing bolt 19. The forward end of the abutment 16 engages the rear face of the bottom lip 5 of the back plate 1 and the construction is such that by loosening the wing bolt 19, the abutment 16 may be moved horizontally thereby varying the angle which the back plate 1 defines with respect to the vertical. Obviously, by inserting the wing bolt 19 into the various openings 10, the position of the abutment 16, vertically considered, may be adjusted, thereby permitting the forward 100 105 110

end of the abutment 16 to engage with the bottom lips 5 of back plates 1 having different heights.

If desired, a spacer 37 may be inserted between the flange 7 of the support 6 and the bottom lip 5 of the back plate 1 for the purpose of adjusting the angle defined by the back plate with respect to the vertical. The spacer 37 may be of wedge-shape if desired, or one spacer of a given cross section may be replaced by another spacer of a different cross section.

A plurality of spacing members 21 are provided the same preferably being in the form of plates. In its lower edge, each spacing plate 21 is provided with a notch 22 defining a finger 23, and in the lower edge of each spacing plate 21 there is a notch 24 defining a finger 25. Adjacent its forward, upper corner, the spacing plate 21 may be provided with an opening 27 adapted to receive a removable key 28 preferably in the form of a pin. A cross pin 26 may be secured in the spacing plate 21 adjacent the rear upper corner thereof.

The invention embodies a front plate 29 which is of less height than the back plate 1, the front plate 29 having a top flange 30 provided with a depending lip 31, and having a bottom flange 32 which may be curved slightly, as shown at 33 in order to shape the place of juncture between the roadbed 35 and the curbing 34. In the top flange 30 of the front plate 29, openings 38 are formed.

In order to assemble the spacing plate 21 with the back plate 1, the upper edge of the back plate 1 is engaged in the notch 22, the finger 23 passing downwardly through the opening 20 and being engaged with the rear face of the back plate. The cross pin 26 lies in an accessible position within the contour of the opening 20 and by engaging a suitable hook (not shown) with the cross pin 26, the spacing plate 21 may be lifted up when desired. The notch 24 in the spacing plate 21 receives the upper edge of the front plate 29, the finger 25 passing downwardly through the opening 38 and coöperating with the forward face of the front plate. When the parts are thus arranged the movable key or pin 28 is inserted through the opening 27 in the spacing plate 21 and engages beneath the top flange 30 of the front plate 29. The coöperation between the parts now is such that the plate 29 will be suspended from the spacing plate 20, the latter being upheld by the back plate 1.

Noting Fig. 2 of the drawings, it will be observed that when the mold is set up for use, the roadbed 35 and the curbing 34 may be fashioned in a single operation and will be permitted to coalesce and form a monolithic union, below the front plate 29.

At times it may be desirable to fashion a roadbed 36, as shown in Fig. 5, with which

no curbing coöperates. Under such circumstances, the spacing plates 21 and the front plate 29 are omitted, the remaining parts of the structure being preserved in the form hereinbefore described.

After the concrete has set sufficient, the pin or key 28 is withdrawn from the opening 27 and the spacing plate 21 and the front plate 29 may then be lifted off, the spacing plate 21 being lifted upwardly out of engagement with the back plate 1.

All parts of the structure, with the possible exception of the spacer 37 preferably are made of metal.

The device herein disclosed is so constructed that it is not necessary to fashion the curbings separately and then to concrete between them to form the roadbed, an operation which at once is costly and inconvenient.

Having thus described the invention, what is claimed is:—

1. A curb form embodying a support; a bracket vertically adjustable on the support; an abutment horizontally adjustable on the support below the bracket; and a back plate detachably interlocked with the bracket, the back plate engaging the abutment.

2. A curb form embodying a support; a bracket vertically adjustable upon the support; an abutment horizontally adjustable on the support below the bracket; a back plate detachably interlocked with the bracket, the back plate engaging the abutment; and a spacer interposed between the support and the back plate and held against lateral movement in one direction by the abutment.

3. A curb form embodying a support; a plate applied to one side of the support and provided with a notch in its upper edge; means for securing the plate to the support in adjusted positions longitudinally of the support; a back plate embodying a depending lip engaged in the notch of the plate; and an abutment adjustable transversely of the support, the abutment coacting with the back plate adjacent its lower edge to hold it spaced from the support.

4. A curb form embodying a support; a plate applied to one side face of the support and provided with a notch in its upper edge; means for securing the plate to the support in adjusted positions longitudinally of the support; a back plate having a depending lip engaged in the notch; and a spacer interposed between the support and the lower end of the back plate.

5. In a device of the class described, a support provided adjacent its lower end with longitudinally spaced openings; an abutment extended transversely of the support and provided with an elongated opening; a securing element adapted for mounting in any of the openings of the support

and engaged in the opening of the abutment; a back plate; means for connecting the upper edge of the back plate with the support; the lower edge of the back plate 5 being engaged by the abutment.

6. In a curb form, a back plate; a front plate provided with a top flange having an opening; a spacing member outstanding from the back plate and provided with a 10 finger extended downwardly through the opening in the flange of the front plate; and

a removable means carried by the spacing plate and engaging the under face of the flange on the front plate for upholding the front plate on the spacing plate.

15

In testimony that I claim the foregoing as my own, I have hereto affixed my signature in the presence of two witnesses.

JOHN N. HELTZEL.
